UNITED STATES PATENT OFFICE.

WILLIAM H. KIRNAN, OF BAYONNE, NEW JERSEY.

ALARM APPARATUS.

No. 918,164.

Specification of Letters Patent. Patented April 18, 1909.

Application filed December 21, 1908. Serial No. 468,437.

To all whom it may concern:

Be it known that I, WILLIAM H. KIRNAN, a citizen of the United States, residing at Bayonne, county of Hudson, State of New Jersey, have invented certain new and useful Improvements in Alarm Apparatus, of which the following is a full, clear, and exact description.

My invention relates to improvements in electric signaling or alarm apparatus, such as call boxes, fire alarm boxes and the like, and has for its object to provide an apparatus for sending signals over an alarm circuit to headquarters, and further to prevent interference between two or more signal transmitters arranged in series on the same circuit.

A further object is to provide an apparatus which will send a signal to headquarters after another simultaneously moving box has sent in a signal, and which will not start if pulled when the circuit is in abnormal condition.

A further object of my invention is to provide a non-interfering alarm signaling apparatus in which a closed circuit signal wheel is used.

At the present time the majority of large cities are using plain interfering signal boxes having closed circuit signal wheels on account of the reliability of the simple form of receiving and recording apparatus at the central station that can be used therewith. Where non-interfering signal apparatus is at present used, the boxes usually have open-circuit signal wheels, that is, wheels in which the circuit is kept open during the pauses between numbers and during some or all the time between signals. This apparatus requires a more complicated receiving and recording apparatus at headquarters for producing records having characters corresponding to the signals recorded.

One of the objects of my invention is to improve both of these systems by providing a complete non-interfering box which can be used upon either without requiring any change in the receiving and recording apparatus at headquarters. It permits the use of the simplest form of direct acting receiving and recording apparatus at headquarters and operates correctly when the specially designed receiving and recording apparatus now required for open-circuit signal wheel boxes is installed.

The following is a description of an embodiment of my apparatus, reference being had to the accompanying drawings, in which,

Figure 1 shows a front elevation of my alarm box equipped with a closed circuit signal wheel. Fig. 2 is an open circuit signal wheel which can be substituted for the closed signal wheel of Fig. 1, although the closed circuit signal wheel, as above stated, is the most desirable. Fig. 3 is a side view 65 of the apparatus of Fig. 1, looking from the left. Fig. 4 is a side detail view of certain parts.

Referring more particularly to the drawings A and B are alarm signal boxes similar 70 in construction but having different signal wheels so as to send in different call numbers.

C is a central receiving apparatus in series with the boxes A and B and a source of current D, the circuit containing the devices A, 75 B, C and D being closed by conductor E. In the box A is a train 1, 2, 3 and 4 driving an escapement wheel 5 with which the escapement 6 engages and driven by a spring 7 in the ordinary manner, the parts being supported by the frames 8 and 9. To the frame 8 is secured a magnet 10 having an armature 11 supported on the rock shaft 12. A back stop 13 for the armature 11 is carried by the frame 8, the back stop being such that the armature when it engages the same is sufficiently out of the field of the magnet 10 so as not to be attracted thereby. A spring 14 connected to the armature support tends to retract the armature 11 so as to cause it to 90 engage the back stop 13. To the armature 11 is connected a member 15, to which is connected a spring member 16. 85

17 is an adjusting screw for adjusting the relation of the flexible member 16 to the part 95 15. The flexible member 16 carries a controller block 18 having a laterally projecting pin 19 for engagement with projections upon the signal wheel. The flexible member 16 has at its lower extremity a pin 20 which 100 under certain circumstances hereafter to be described engages a pin 21 carried by the fan 22 which is mounted upon the shaft of the escapement 6, so as to block the movement of the fan 22 and thereby block the train. 105 The block 18 on the flexible member 16 carries a projection or controller pin 23 of insulating material which is adapted to engage a spring contact 24 and separate it from the contact 25 so as to break the circuit through 110

the magnet 10 and the similar magnets in other boxes in series therewith. The contacts 24 and 25 are mounted on an insulating block and are in series with the magnet 10 and the transmission circuit. The parts 18, 19 and 23 constitute the controller for the contacts. The wheel 3 carries a lug 26.

27 is a pawl carried by a lever 28 and having its movement limited by pins 31 and 31^a. 10 When the lever 28 is in the depressed position shown, the pawl 27 is engaged by the lug 26 so as to stop the train. The lever 28 is held in depressed position by spring 29 and the pawl 27 when not in engagement with the lug 15 26 is drawn forward by the spring 30 until its laterally projecting arm engages the pin 31 upon the lever 28. The lever 28 carries a pin 32 which engages with a cam surface 33 carried by the main gear 1. The cam 33 has 20 two diametrically opposite slots, as shown in Fig. 1. When the lever 28 is raised by pulling the hook 34 downward, the pawl 27 is withdrawn from the lug 26 and if the magnet 10 is energized, the train begins to move. 25 The pin 32 then rides upon the outer surface of the cam 33 and holds the lever 28 in elevated position until the next recess in the cam comes around, at which time the lever 28, unless otherwise restrained, descends so 30 that the pawl 27 lies in the path of the lug 26. The gears are so proportioned that one-half revolution of the gear 1 produces four revolutions of the gear 3. The signal wheel 35 is connected to the shaft of the gear 3 and 35 therefore revolves four times whenever the hook 34 is pulled. The wheel 35 has projections 36 corresponding to the call number of the box. In the call box A the number is thirty-five, there being three projections 36 40 followed by a space, which is followed by five other projections 36.

When the pin 19 is in the position shown, the projections 36 as the wheel 35 revolves engage the pin 19 and force the controller 23 45 against the spring contact 24 so as to separate it from the contact 25, first three times, then after a short pause five times, sending in the call of the box. If, however, the circuit through the magnet 10 is broken after 50 the box has started but before the first projection 36 reaches the pin 19, the armature 11 will be fully retracted, and the pin 19 will be moved so as to lie within the circumference described by the inner portions of the 55 projections 36. The projections 36 will therefore pass the pin 19 without touching the same or affecting the contact 24. 37 is a cam surface on the wheel 35, which when the pin 19 lies within the inner circumference described by the projections 36 engages the pin 19 and forces it outward, bringing the armature 11 into the field of the magnet 10, so as to be attracted thereby if the magnet 10 is energized. If in the next revolution 60 of the wheel 35, the first projection 36

reaches the pin 19 before the magnet 10 has become deenergized for any cause the wheel 35 will engage the pin 19 and actuate the spring contact 24 so as to send in its signal, except under other conditions hereinafter 70 described.

The outer end of the cam 37 forms a projection so located that when the magnet 10 is deenergized and continues to be deenergized for some little time, as for instance, 75 when the circuit is broken on account of repairs being made, the pin 20 at the lower end of the member 16 comes into the path of the projection 21 upon the fan 22 thereby restraining the same together with the train 80 from movement. This inward movement of the pin 19 is sufficient to carry a spring pawl 38 mounted on the arm 39 inward so as to engage the end of the lever 28 when the same is raised by the hook 34 and hold 85 it in elevated position.

The pawl 38 is pivoted to the arm 39 and is held in normal position by the spring 40 bearing on its rear side. If on account of the repairing of its circuit, the magnet 10 is 90 deenergized at the time hook 34 is pulled, the pawl 38 holds the lever in elevated position until the magnet is again deenergized. The train meanwhile being restrained from movement by the engagement of the pin 20 with the pin 21, as above described. As soon as the magnet 10 is again energized, 95 the lever 28 is released by the pawl 38 and the pin 20 is moved out of the path of the pin 21. The lever 28 is however still held 100 in raised position because the pawl 27 has been moved by its spring 30 so as to be above the lug 26. The train is therefore free to operate and send in a signal of the box although the lever 34 was pulled during 105 the repair intermission. Before the lug 26 passes from beneath the pawl 27, the pin 32 has engaged the cam 33 so as to hold the lever 28 elevated after the lug 26 has passed from beneath the pawl 27. 41 is a lug also 110 carried by the signal wheel 35 with the inner side of which the pin 19 engages under certain circumstances. This lug 41 is so located that when the pin 19 is in engagement therewith, it prevents the armature 11 115 from being fully attracted, so as to withdraw pawl 38 from lever 28, but does not hold the pin 20 in the path of the pin 21 so as to stop the movement of the train during the starting of the operation. The lug 41 120 thus insures against having the pawl 27 drop so as to engage the edge of lug 26 at the end of a silent cycle so that after a silent cycle four audible calls will be sent in. After the hook 34 has been pulled, the pawl 125 27 will ride on the outer surface of the lug 26 and will keep the point of the lever 28 slightly elevated above the detent 38 until the cam 33 engages the pin 32, which engagement takes place just before the pawl

27 leaves the lug 26. In some cases it is desired to have the box stop at the end of four rounds. In such cases the members 38, 40 and 41 and the lower part of 39 can be omitted.

The operation is as follows: First assume that the circuit through the magnet 10 is closed so that the armature 11 will be attracted thereby: When the hook 34 is pulled, 10 it elevates the lever 28 so as to release the pawl 27 from its engagement with the lug 26. This causes the lever 28 to rise sufficiently to clear the lug 26. The disengagement of the lug 26 allows the train to move and continue 15 on its course during which time the pin 19 will engage with the projections 36 and the cam 41 on the wheel 35. At each engagement of the pin 19 with the projections 36, the contacts 24 and 25 will be separated, 20 thereby causing the signal call number "thirty-five" to be transmitted over the circuit. This movement will continue its performance four times sending in its signal "thirty-five" each time and when it has 25 completed its four signals, the pin 32 will fall into the next recess in the cam 33 early enough to permit the pawl 27 to engage the lug 26. Presuming that the circuit has an earlier engagement from the operation of 30 some other signal box, the operation of the second box pulled will be as follows: After being released by the hook 34, the armature 11 if the circuit at that time is open will be partially retracted by spring 14 to a distance 35 allowed by the outer end of the cam 37 which distance permits the pin 20 to come into engagement either above or below the pin 21 thereby holding the movement of the box temporarily stopped. As soon as a 40 temporary closure is made by the distant signal box during its operation, armature 11 will be attracted by magnet 10, which will cause projections 20 and 21 to become disengaged. This permits signal box A to start 45 again and during its operation the pin 19 will become disengaged from the cam 37. If the circuit at the distant box is again open before the first projection 36 upon the signal wheel 35 reaches the pin 19, the pin 19 will 50 fall inside the path of the projections 36, thereby letting the armature 11 fall out of the magnetic field of the magnet 10 and rest on the adjusting screw 13. This condition will exist during the revolution of the signal 55 wheel 35 until pin 19 comes into engagement with cam 37, when it will be seen that the armature 11 will be brought back into the field of magnet 10. If at that time the circuit should be interrupted at a distant 60 point, the operation on the next revolution of the signal wheel 35 will be the same as the previous revolution; but if the circuit should happen to be closed temporarily at that time for a period long enough to permit pin 19 to 65 be engaged by the first projection 36 on the

signal wheel 35, the box A will take control of the circuit and send in its signal "thirty-five."

It will be seen that in signal apparatus of this character, there is an important possibility of two boxes alternating between signals, that is, one box may send in its call once and another box may then step in and send in its call. This can not, however, be considered an interruption or confusion for at no 75 time can any single signal be mutilated.

The possibility of the alternations of signals is a great advantage when signal boxes run into high numbers as there might be two boxes pulled at or about the same time for 80 different fires at different locations. If it so happened that this period of duration did not arrive so as to permit alternations, the second or silent box which would be waiting to perform service would continue in its effort to 85 send in a signal until the line becomes closed. If at such time the second box pulled was at the finish of its fourth silent revolution and with its armature 11 lying out of the field of the magnet 10, it will be seen that lever 28 of 90 that box will be lying above the pawl 38 and since the armature 11 of that box will not be attracted to magnet 10 in time to release its lever 28, to stop the operation of the box, further precaution is taken to overcome 95 closeness of operation as follows: The pawl 27 will be in advance position caused by spring 30 forcing it forward so that when armature 11 is finally brought into the field of magnet 10 and is fully attracted thereby 100 on account of the circuit being closed, pawl 38 will release lever 28, but not before pawl 27 has reached and rides upon lug 26. This permits the boxes to proceed and send in 105 four audible signals.

The operation of two boxes being both at exactly the same time is not similar to all other boxes of this character, the one having the largest points of interruption on its signal wheel in the first number of the signal 110 will take precedence of the box with a lower first number for the reason that any box which will open the circuit during operation at a distant point will cause any other box to cut itself out of electrical operation; thus if 115 the circuit is closed in box A when the space between the third and fourth projection 36 is passing and at that time the circuit is open at some other box such for instance as a box having the call number "fifty-three", the 120 pin 19 of the box A will be drawn within the inner circle described by the projections 36 and the box A will continue to operate without any electrical effect as before described.

If the circuit becomes disturbed for a 125 longer period than that which is required to send in a signal, such as an interruption caused by an accident, blowing out of a fuse at headquarters, alterations or repairs and a box is pulled during this time, the box would

be released and placed in position for operation when the circuit was completed but no movement would take place until such completion because the armature 11 would be withdrawn from the magnet 10 by the spring 14 bringing the projections 20 and 21 into engagement and thereby stopping the action of the box. The movement of the pin 21 being limited by the engagement of the pin 19 with the outer end of the cam 37 so that it will stop in the proper position for such engagement. Such movement does not take the armature 11 out of the magnetic field of the magnet 10 and therefore when the circuit has been restored the armature 11 will be attracted by the magnet 10 disengaging the projections 20 and 21 and permitting the box to send in its signal.

It is to be noted that the signal wheel of box A is a closed circuit signal wheel, by which is meant a signal wheel which permits the circuit to be closed during pauses between numbers and between signals. An open circuit signal wheel is shown in Fig. 2. By such a wheel the circuit is kept open between numbers and also between signals. It has been the practice in non-interfering fire alarm systems to use open circuit signal wheels. By my invention, however, I am able to use a closed circuit signal wheel in such systems. A closed circuit signal wheel is greatly to be desired for the reason that a simpler receiving apparatus may be used at the central station for producing a record in which the signal is represented by characters as distinguished from spaces. Furthermore, a closed circuit signal wheel can be used in connection with any central station receiving apparatus which will receive the signals from an open signal wheel.

In my apparatus I secure non-interference of signals by preventing the box from beginning its electrical operation after being manually released until a distant box already in operation has almost covered the entire distance of the pause between rounds. My box will not interfere with boxes upon the same line even though such boxes be interfering boxes using closed or open circuit signal wheels and ordinary recording apparatus at the central station but will work in harmony with such apparatus cutting itself out if a distant interfering box is already in operation and cutting itself out in case it is started at the same time as an interfering box. If an interfering box is pulled while my box is in operation, the worst that can happen is the mutilation of one signal since my box will cut itself out of operation in case of interference and will later go on and send in its own signal. My box will also work in perfect harmony on a circuit with boxes using open circuit wheels and their specially designed central station receiving apparatus. In either case the non-interfering feature is

maintained whether a closed circuit wheel or open circuit wheel is used.

The purpose of the cam 41 is to prevent the armature 11 from being fully attracted so as to cause the pawl 38 to release the lever 28 in time for pawl 27 to engage end of lug 26 in case an audible round of box B terminates while the pin 19 of box A is within the cam 41.

Fig. 2 shows an open circuit signal wheel. In this figure 36^a and 36^b are the projections 75 engaging the pin 19. The projections 36^b are extended, one of them holding the circuit open during the whole period after the third interruption until just before the fourth interruption. The second holds the 80 circuit open from the time of the last interruption until the signal wheel reaches its normal position. This signal wheel can be substituted for the signal wheel 35 of Fig. 1 if desired, but as above stated my invention 85 is particularly adapted and intended to permit the use of closed circuit signal wheels with their many advantages. With open signal wheels, the box having a higher first 90 number is the one which cuts itself out automatically when two boxes are started at the same time, since the circuit would be closed at such a box when open at the between number interval of a box having a smaller first number. When the wheel 35 95 is in normal position the distance between the pin 19 and the first projection 36 is greater than the distance between the pin 19 and the last projection 36. The time that it takes for the first projection 36 to reach the 100 pin 19 is known as the "delay" of the box. This delay is longer than any pause between numbers and more than half as long as the pause between rounds or signals. This long delay in my box prevents one box from 105 mutilating the signals of another box.

What I claim is:

1. The combination of a closed circuit signal wheel, a non-interfering magnet, an armature therefor, a controller connected to said armature and actuated by said wheel, and circuit contacts in series with said magnet and controlled by said controller.

2. The combination of a closed circuit signal wheel, a controller actuated thereby, circuit contacts controlled by said controller, an armature connected to said controller, a magnet for said armature in series with said contacts and means tending to withdraw said armature from the range of the normal field of said magnet, and remove the controller from the range of the signal wheel.

3. The combination of a transmission circuit, separable contacts therein, a controlling member for disengaging said contacts, a signal wheel for actuating said member, an armature to which the controlling member is yieldingly connected, a magnet attracting said armature upon the closing of said circuit when said armature is within the field of 130

said magnet, means for withdrawing said armature from the normal range of said field, said signal wheel having projections engaging said controlling member when said 5 armature is within said field, said controlling member being out of range of said projections when said armature is out of said field.

4. The combination of a transmission circuit, separable contacts therein, a controlling member for disengaging said contacts, a signal wheel for actuating said member, an armature to which the controlling member is yieldingly connected, a magnet attracting said armature upon the closing of said circuit when said armature is within the field of said magnet, means for withdrawing said armature from normal range of said field, said signal wheel having projections engaging said controlling member when said 15 armature is within the field, said controlling member being out of range of said projections when said armature is out of said field, said signal wheel having also a cam surface for returning said armature to said field 25 when removed therefrom.

5. The combination of a transmission circuit, separable contacts therein, a controlling member for disengaging said contacts, a signal wheel for actuating said member, an armature to which the controlling member is yieldingly connected, a magnet attracting said armature upon the closing of said circuit when said armature is within the field of said magnet, means for withdrawing said 35 armature from the normal range of said field, said signal wheel having projections engaging said controlling member when said armature is within said field, said controlling member being out of range of said projections when said armature is out of said field, said signal wheel having a projection which when the wheel is in normal position holds said armature within the range of the normal field of said magnet when said magnet 45 is deenergized.

6. The combination of a transmission circuit, separable contacts therein, a controlling member for disengaging said contacts, a signal wheel for actuating said member, an armature to which the controlling member is yieldingly connected, a magnet attracting said armature upon the closing of said circuit when said armature is within the field of said magnet, means for withdrawing said 55 armature from the normal range of said field, said signal wheel having projections engaging said controlling member when said armature is within said field, said controlling member being out of range of said projections when said armature is out of said field, said signal wheel having also a cam surface for moving said armature into said field when removed therefrom and a projection which when the wheel is in normal position holds said armature within range of the normal 65

field of said magnet when said magnet is deenergized.

7. The combination of a transmission circuit, separable contacts therein, a controlling member for disengaging said contacts, a signal wheel for actuating said member, an armature to which the controlling member is yieldingly connected, a magnet attracting said armature upon the closing of said circuit when said armature is within the field of said magnet, means for withdrawing said armature from the normal range of said field, said signal wheel having projections engaging said controlling member when said armature is within said field, said controlling 75 member being out of range of said projections when said armature is out of said field, a pawl for controlling the train driving said signal wheel, means for withdrawing said pawl and a detent carried by said armature 80 and restraining said pawl when said pawl is lifted at a time when the armature is withdrawn from said magnet.

8. In a combination of a transmission circuit, separable contacts therein, a controlling member for disengaging said contacts, a signal wheel for actuating said member, an armature to which the controlling member is yieldingly connected, a magnet attracting said armature upon the closing of said circuit, when said armature is within the field of said magnet, means for withdrawing said armature from the normal range of said field, said signal wheel having projections engaging said controlling member when said armature is within said field, said controlling member being out of range of said projections when said armature is out of said field, a lever, a spring pawl carried thereby for controlling the train driving said signal 95 wheel, means for lifting said lever, a detent carried by said armature and restraining said lever when said lever is lifted at a time when the armature is withdrawn from said magnet.

9. The combination of a transmission circuit, separable contacts therein, a controlling member for disengaging said contacts, a signal wheel for actuating said member, a driving train therefor, an armature to which the controlling member is yieldingly connected, a magnet attracting said armature upon the closing of said circuit when said armature is within the field of said magnet, means tending to withdraw said armature from the normal range of said field, said signal wheel having projections engaging said controlling member when said armature is within said field, said controlling member being out of range of said projections when said armature is out of said field, said signal 110 wheel having a stop projection which when the wheel is in normal position is engaged by said controller and holds said armature within the range of the normal field of said magnet when said magnet is deenergized, 115 120 125 130

said controlling member having means for blocking said train when engaged by said last named projection.

10. The combination of a transmission circuit, separable contacts therein, a controlling member for disengaging said contacts, a signal wheel for actuating said member, a driving train therefor, an armature to which the controlling member is connected, a magnet attracting said armature upon the closing of said circuit when said armature is within the field of said magnet, means for withdrawing said armature from said field, said signal wheel having projections engaging said controlling member when said armature is within said field, said controlling member being out of range of said projections when said armature is out of said field, said signal wheel having a projection which when the wheel is in normal position holds said armature within the range of the normal field of said magnet when said magnet is deenergized, said controlling member having means for blocking said train when engaged by said last named projection, said signal wheel also having a projection holding said armature away from said magnet but in a position where said controlling member does not block said train.
- 30 11. The combination of a transmission circuit, separable contacts therein, a controlling member for disengaging said contacts, a signal wheel for actuating said member, an armature to which the controlling member is yieldingly connected, a magnet attracting said armature upon the closing of said circuit when said armature is within the field of said magnet, means for withdrawing said armature from the normal range of said field, said signal wheel having projections engaging said controlling member when said armature is within said field, said controlling member being out of range of said projections when said armature is out of said field, 45 a pawl for controlling the train driving said signal wheel, means for withdrawing said pawl, and a detent carried by said armature and restraining said pawl when said pawl is lifted at a time when the armature is withdrawn from said magnet, said signal wheel having a stop projection adapted to hold the

armature within the normal range of the field of said magnet when the controlling member engages said stop projection.

12. The combination of a circuit signal wheel, a controller actuated thereby, circuit contacts controlled by said controller, an armature connected to said controller, a magnet for said armature in series with said contacts, and means tending to withdraw said armature from the range of the normal field of said magnet, and remove the controller from the range of the signal wheel, the delay of the signal wheel being longer than the pause between numbers.

13. The combination of a circuit signal wheel, a controller actuated thereby, circuit contacts controlled by said controller, an armature connected to said controller, a magnet for said armature in series with said contacts, and means tending to withdraw said armature from the range of the normal field of said magnet, and remove the controller from the range of the signal wheel, the delay of the signal wheel being longer than the pause between numbers and more than half as long as the pause between rounds or signals.

14. The combination of a magnet, a three position armature therefor, a circuit signal wheel, a controller actuated thereby and connected to said armature, said signal wheel having signal projections actuating said controller when said armature is in attracted position, said signal wheel when said magnet is deenergized at times permitting said armature to be only slightly withdrawn from said magnet and retaining it so withdrawn within range of the normal field of said magnet, and at other times to be withdrawn from the range of said normal field, circuit contacts controlled by said controller and in series with said magnet, and means tending to withdraw said armature from the range of the normal field of said magnet and to remove the controller from the range of the signal projections on said signal wheel.
